UNITED STATES PATENT OFFICE

2,098,075

WASHING MACHINE

Noble H. Watts, Bridgeport, Conn., assignor to
 General Electric Company, a corporation of
 New York

Application May 29, 1934, Serial No. 728,125

1 Claim. (Cl. 74—78)

My invention relates to power driven washing and wringing machines and particularly to washing and wringing machines of the type wherein the washing is performed by an agitator member which is mounted within the tub containing the material to be washed and given an oscillatory motion with respect thereto, and the wringing is performed by a suitable wringer carried by the supporting structure of the machine. The washing mechanism and the wringer are usually driven by a small electric motor and my invention relates particularly to a machine so driven, but it will be understood that it is not necessarily limited thereto, nor is it as to certain aspects limited to the specific type of washing mechanism referred to above.

The object of my invention is to provide an improved washing and wringing machine, and for a consideration of what I believe to be novel and my invention, attention is directed to the accompanying description and the claim appended thereto.

In the drawing Fig. 1 is a vertical sectional view partly broken away of a machine embodying my invention, the section being taken on line 1—1 of Fig. 2; Fig. 2 is a plan view of the machine partly in section with certain parts broken away or removed to illustrate those below; Fig. 3 is a detailed sectional view taken on line 3—3 of Fig. 30 1 and Fig. 4 is an enlarged sectional detail view taken on line 4—4 of Fig. 3.

Referring to the drawing, 10 represents a gear case comprising an elongated housing member of irregular shape which extends diametrically across the under side of tub 11 and is connected at its ends to legs 12 and 13 so as to form a bridge-like rigid supporting structure for the tub. A rolled steel skirt 14 is fastened to the gear case and the legs by screws as indicated at 15, and other suitably spaced legs (not shown) are fastened to the steel skirt at the front and at the rear of the machine to complete the supporting structure. The upper periphery of steel skirt 14 is flanged as shown at 16 to provide a peripheral support for the tub, which is centrally supported by the gear casing in a manner to be described later. A gasket of insulating or sound deadening material 17 is preferably arranged between flange 16 and the tub. Centrally of and below casing 18 is arranged a driving motor consisting of a stator member 18 and a rotor 19, the rotor being carried by a vertical shaft 20. Although the motor may be supported in any desired manner, I prefer to form the upper end bell of the motor integrally with the gear casing and to attach

stator 18 and the lower end bell of the motor thereto by means of a plurality of stud bolts which are threaded into bosses (not shown) on the unitary upper end bell, or, viewed from another aspect, the surrounding motor shell is bolted directly to the gear casing. The head of one of these connecting bolts is indicated at 21. In order to further brace the supporting structure, a number of radially extending rods 22 are connected at one end to the gear casing or motor frame as shown at 23 and at the other end to the supporting legs as shown at 24.

The upper side of gear casing 10 is provided with an elongate opening 25 as shown best in Fig. 2 over which a cover member 26 is arranged. Cover 26 may be fastened to the gear casing in any desired manner as by a plurality of stud bolts which are adapted to thread into holes 27 in the casing. I prefer to employ a gasket between the gear casing and its cover in order to provide an oil tight closure.

At the central position of the supporting cover member 26 a raised portion 27 is provided having an aperture therein in which is arranged an assembly unit for supporting the center of the tub. The assembly unit comprises a bearing member 28 provided with a flanged portion 29 arranged below the cover and with a tubular threaded portion extending upward through the aperture in the cover. An internally threaded center post 30 is provided with a flange 31 immediately above cover member 26 so that when center post 30 is screwed down on bearing 28 cover member 26 will be clamped between flanges 29 and 31 whereby bearing member 28 and center post 30 are supported centrally of the bridging structure by cover 26. The upper side of flange 31 forms the center support for tub 11 which is provided with an aperture through which center post 30 extends upwardly. Threaded on center post 30 is a flanged nut 32 which bears against the upper side of the bottom of the tub to complete the assembly unit. Gasket members 33 may be arranged respectively between the tub and flange 31 and between the tub and flange nut 32 in order to provide a water tight joint. It will be seen, therefore, that I have provided a compact, braced supporting structure for a washing machine which includes a gear case extending across the bottom of the tub to centrally support the same and a peripheral skirt carried by the gear case for supporting the periphery of the tub, in which two legs are fastened to the gear case to form a bridge and the other two legs are fastened to the peripheral skirt, all of the legs being

bound to a motor frame suspended centrally of the gear case.

Journalized in bearing 28 is an oscillating shaft 34 which is arranged in vertical alignment with 5 motor shaft 20 with its lower end bearing on the upper end of said shaft. The respective ends of the two shafts are ground flat to provide smooth even bearing surfaces. The upper end of motor shaft 20 is journaled in a bearing 49 carried in a boss 50 in the gear casing. A retaining ring 51 is provided which is located in a groove in shaft 20 just above bearing 49. It normally clears bearing 49. Its purpose is to hold shaft 20 from dropping out of its bearing when the 15 machine is being assembled or dismantled. By reason of the vertical alignment of the two shafts 20 and 34 a compact gear train consisting entirely of helical or spur gears and a rack and pinion may be utilized for converting the rotary 20 motion of shaft 20 into oscillatory motion for shaft 34. The gearing mechanism comprises a helical gear 36 cut into the motor shaft 20 and meshing with gear 37 which is journaled on a pin 38 rigidly mounted in boss 39 formed in the 25 gear casing. Gear 37 carries a spur pinion 40 which is made integral therewith by forcing the pinion into the gear so that the teeth of the pinion cut their way in and act as keys or splines. If the gear is die cast the pinion may be molded 30 in the gear as an insert. Meshing with pinion 40 is a gear 41 which is journaled on pin 42 and which carries an eccentrically mounted pin 43 on which is journaled a rack frame 44. It will be seen that by means of the mechanism thus 35 far described the rotation of motor shaft 20 is transmitted through the reducing gears and pinions to gear 41 which reciprocates rack frame 44 by means of stud 43. Rack teeth 45 are arranged along one side of frame 44 so as to mesh 40 with a pinion 46 carried by shaft 34 whereby shaft 34 is oscillated. Although pinion 46 may be mounted on shaft 34 in any suitable manner I prefer to provide shaft 34 with splines, as shown, and to hold pinion 46 against the under 45 side of bearing 28 in correct alignment with rack 45 by means of a nut 46a threaded on shaft 34. In order to transmit oscillating movement to shaft 34 and to balance the thrust exerted by the rack teeth 45 on pinion 46, I provide a guide lip 50 or flange 47 along the side of frame 44 opposite from the rack teeth 45 arranged to bear against the outer raceway of an anti-friction bearing 48 carried by shaft bearing 28, whereby rack 45 will be held in contact with pinion 46 and the tooth 55 thrust on one side of shaft 34 will be transmitted to the roller bearing 48, thereby balancing the tooth strains with the roller strains. It will be realized of course that the particular arrangement shown is merely one embodiment of my 60 invention, and that roller bearing 48 may be mounted directly on shaft 34, or may be entirely dispensed with and an annular shoulder on shaft 34 or bearing 28 substituted therefor. When the gearing is assembled, shaft 20 is supported 65 by the engagement of the single helical teeth of pinion 36 with the single helical teeth on gear wheel 37. The angle of these teeth is such that when the motor is running there is an axial thrust upward on shaft 20. This upward axial thrust is taken by shaft 34.

70 The outer raceway of roller bearing 48 may have a diameter equal to or smaller than the diameter of pinion 46 so long as guide lip 47 is so located as to bear against the raceway to maintain pinion 46 in contact with rack 45. I

have found it advisable, however, to make roller bearing 48 of slightly greater diameter than pinion 46 in order to facilitate assembly of the unit. If roller bearing 48 is given a smaller diameter than pinion 46 guide lip 47 must project inwardly 5 over pinion 46 in order to contact with the raceway. With a larger diameter raceway, guide lip 47 does not extend inwardly over pinion 46 and the whole assembly unit comprising bearing 28, shaft 34, roller bearing 48, pinion 46 and nut 10 46a may be first assembled and then lowered into position without interference from guide lip 47 so that the lower end of shaft 34 rests on shaft 20. The arrangement of the thrust absorbing roller bearing 48 on the same shaft as the pinion 15 46 and concentrically therewith results in a simple compact structure which is easily alignable to impart uniform oscillation to shaft 34. The full angular throw of reciprocating frame 44 around pinion 46 as a center results in a lower 20 power loss due to fewer friction points.

Surrounding oscillator shaft 34 is a tubular upright stem 52 which is carried by center post 30, a press fit being provided therebetween. The upper end of stem 52 carries a bushing 53 in 25 which is journaled an enlarged portion 54 of shaft 34 as shown in Fig. 4. Immediately below portion 54 I provide a combined sealing and supporting structure for shaft 34, which comprises a coil spring 55, one end of which bears against 30 a washer 56 supported on an internal annular shoulder 57 formed in stem 52. The other end of coil spring 55 bears against a cup-shaped washer 58 surmounted by a rubber ring 59 and a ground 35 steel ring 60. Coil spring 55 forces ground steel ring 60 upward into contact with enlarged portion 54 to support the shaft against downward thrust. The expansion of rubber ring 59 under the force exerted by coil spring 55 forms a water 40 tight joint between the ring and stem 52 and together with the ground joint between steel ring 60 and portion 54 prevents the entrance of water into the gear case 10 by way of stem 52.

Immediately above bushing 53 shaft 34 is further enlarged to provide a driving head 61. Positioned on driving head 61 and adapted to be driven thereby is a vane type agitator 62. Any suitable vane type of agitator may be used. An annular supporting ring 63 carried by the agitator serves to properly position the lower end of agitator 62. The ring fits over the upper end of post 30 which serves as a bearing for it. The agitator is centered at its upper end by driving head 61. On the upper end of the agitator is a control rod 64 which extends into a socket 65 reamed in the head. Attached to the upper end of control rod 64 is a control knob 66 slidably journaled in the upper end of the agitator at 67. Rod 64 is free to turn in knob 66 so that when the knob is grasped in the hand it does not turn 50 therein even if rod 64 is oscillating. Arranged within the agitator between the upper end thereof and driving head 61, I have provided a clutching mechanism adapted to be operated by control rod 64 for connecting the agitator to and disconnecting it from oscillating shaft 34 so as to at will 55 impart to agitator 62 the oscillatory motion of shaft 34. The upper face of driving head 61 is provided with two arcuate slots 68 and a key block 69 is pressed into the agitator head and 60 provided with four holes 70 spaced 90° apart and circumferentially arranged around a central aperture 71 in block 69 through which slides control bar 64. A plurality of clutch plungers 72 65 slidably arranged in the holes 70 for providing a 70

driving connection between the shaft and the agitator, are connected to control rod 64 for actuation thereby through a disk 74 carried by the control rod. As shown in Fig. 1 the upper end of each plunger 72 extends through disk 74 and is provided with an enlarged portion above disk 74 whereby the plungers 72 will be pulled when control rod 64 and disk 74 are lifted. Each plunger is provided with a coil spring 73, one end of which 5 bears against the under side of disk 74 and the other end of which bears against a shoulder 72a on the respective plungers 72. When control rod 64 is moved, by depressing control button 66, disk 74 moves downwardly with control rod 64 and compresses coil springs 73 whereby plungers 72 10 are forced through holes in key block 69 into engagement with arcuate slot 68 in driving head 61. Each arcuate slot 68 spans an arc of 90° plus the diameter of one of the plungers 72 so that 15 when plungers 72 are depressed the ends of each slot will cooperate with a pair of plungers to positively drive the agitator with a reversing motion. Plungers 72 are provided with tapered ends to cooperate with the tapered sides of slots 68 in order to compensate for wear and to allow 20 clearance for engagement. When control knob 66 is lifted disk 74 will move with control rod 64 and plungers 72 are pulled upward out of engagement with arcuate slot 68 to disengage the 25 agitator from the oscillating shaft 34. As shown in Fig. 4 a toggle mechanism is provided for biasing control rod 64 to either clutched or unclutched position. This toggle mechanism consists of a pair of levers 75 pivotally connected to 30 control rod 64 and connected at their free ends to springs 76 which are attached by means of rivets 77 or other suitable means to key block 69.

The operation of the clutch mechanism may be described as follows: Assume a moment of engagement in which two opposite plungers coincide with the center of slots 68 and the two other plungers lie along line 4—4 of Fig. 3. It is evident that when control button 66 is depressed the first two plungers are free to move downwardly into the arcuate slots 68, but the two plungers along line 4—4 are stopped by the head and their springs are compressed. When the driving head has rotated sufficiently to bring the first two plungers into contact with the respective ends of arcuate slots 68 the remaining two plungers will then be in alignment with the opposite ends of slots 68 and will be moved into engagement by springs 73 so that when the motion of shaft 34 is reversed the two latter plungers take the driving effort. By utilizing arcuate slots in the driving head and providing a plurality of suitably spaced clutch plungers each having an individual resilient lost motion connection with the control rod, I have provided a clutch mechanism in which the control button may be actuated at any moment regardless of the position of the oscillating driving head, and in which the clutch plungers will always move to driving position regardless of the speed of the driving head. I have found that if a plurality of holes are provided in the driving head in place of arcuate slots 68 considerable difficulty is encountered in that the clutch plungers will often slide right over the holes which are moving at high speed and the clutch will not become engaged. It will be obvious that any number of arcuate slots and pairs of cooperating plungers may be used so long as the length of each slot is equal to the spacing of a pair of plungers.

In order to insure that the control knob will

remain in either of its extreme positions whether or not the clutch plungers are engaged, it is necessary to make the toggle springs 76 somewhat stiffer than the pin backing springs 73. With a strong toggle spring it has been found 5 that there is a tendency for the agitator to be lifted off the driving head when control button 66 is lifted to disengage the clutch. In order to prevent the agitator from being so lifted from the driving head, I have provided an annular 10 groove 78 in the driving head 61 which cooperates with a snap ring 80 and a similar annular groove 79 in the agitator. Snap ring 80 which is placed in groove 79 has a maximum diameter slightly 15 larger than driving head 61 and is free to collapse so that the agitator may be forced downward thereover into correct position. With the agitator in correct position with respect to the driving head snap ring 80 will expand into groove 79 whereby a detachable connection is established 20 which will maintain the agitator in this position against the pull which is necessary to disengage the clutch mechanism and which will permit easy removal of the agitator from the tub on the exertion of a stronger pull. 25

My improved washing machine also includes a wringer mechanism, not shown, which is driven from the same electric motor through a portion of the same gear train which drives oscillating shaft 34. As shown in Fig. 1 a vertical rotary 30 shaft 81 for driving the wringer is journaled at 82 in a boss carried by an extension of gear case 10. The lower end of shaft 81 rests on the lower wall of gear case 10 and carries gear 83 threaded thereon which is driven from gear 41 by means 35 of an idler gear 84. Idler gear 84 is fixedly connected to a rotating pin 85 which rotates in sockets 86 and 87 formed respectively in bosses in the lower and upper walls of gear case 10. The extension of gear case 10 which carries the wringer 40 driving gears 83 and 84 comprises spaced walls 88 and 89. The assembly of the gears in the proper alignment between walls 88 and 89 is accomplished as follows:

Gear 83 is first slid into the narrow space between walls 88 and 89 and wringer shaft 81 is lowered through its bearing 82 and connected to gear 83 by means of the cooperating threads on the gear and the shaft. Gear 84 is then placed between walls 88 and 89 in mesh with gear 83 50 and pin 85 is inserted through the top of socket 87. In order to fixedly connect gear 84 to pin 85 a ball and pin arrangement is provided comprising ball 90 and threaded pin 91. When pin 91 is screwed down in rotatable pin 85 the rounded end of pin 91 forces ball 90 into tight engagement with gear 84 whereby gear 83 is caused to turn with pin 85. It will be seen that I have provided a simplified compact arrangement for transmitting rotation to the wringer shaft which 55 may be easily assembled in the closed extension of gear casing 10.

In order to properly ventilate the electric motor and to prevent leakage of oil from the gear case through bearing 49, I provide a combined 65 ventilating fan and oil seal comprising a hardened steel ring 92 which is pressed against the lower end of bearing 49 by means of spring 93 and is connected by flexible diaphragm 94 to the edge of fan 95 which is pressed onto the motor shaft. 70

A water drain 96 is provided in the bottom wall of tub 11 to which is attached a conduit or hose 97 leading to pump housing 98 which is fastened to the lower end bell of the electric motor in any suitable manner as by screws 99, the lower end 75

bell of the motor serving as the upper wall of the pump housing. The lower end of motor shaft 20 is journaled in bearing 100 and extends into pump housing 98. A suitable centrifugal pump element 101 is carried by shaft 20 within the pump housing and serves to exhaust the water from tub 11 when valve 102, located in the discharge line of the pump, is opened. An oil seal similar to the one described above is built into pump element 101 in order to prevent the leakage of oil from reservoir 103 into the pump housing.

In accordance with the provisions of the patent statutes I have described the operation of my invention together with the apparatus which I 15 now consider to represent the best embodiment

thereof, but I desire to have it understood that the apparatus shown is only illustrative and that the invention may be carried out by other means.

What I claim as new and desire to secure by Letters Patent of the United States, is:

5 In a washing machine, a rotary driving shaft, an oscillatory driven shaft, means including a rack and pinion connecting said shafts for oscillating said driven shaft, said shafts being arranged in vertical alignment with an end of said 10 driving shaft bearing against an end of said driven shaft to provide a thrust bearing for said shafts.

NOBLE H. WATTS.
